UNITED STATES PATENT OFFICE.

GEORGE LIGHTHISER, OF NAPOLEON, OHIO.

CAR-COUPING.

SPECIFICATION forming part of Letters Patent No. 284,644, dated September 11, 1883.

Application filed February 17, 1883. (No model.)

To all whom it may concern:

Be it known that I, GEORGE LIGHTHISER, a citizen of the United States, residing at Napoleon, in the county of Henry and State of Ohio, have invented a new and useful Car-Coupling, of which the following is a specification, reference being had to the accompanying drawings.

This invention relates to car-couplings; and it consists in certain improvements in the construction of the same, which will be hereinafter fully described, and particularly pointed out in the claim.

In the drawings hereto annexed, Figure 1 is a perspective view. Fig. 2 is a bottom view of my improved car-coupling. Fig. 3 is a longitudinal sectional view. Fig. 4 is a transverse sectional view. Fig. 5 is a horizontal sectional view, and Fig. 6 is a perspective view illustrating my invention applied to serve as a gate-latch.

The same letters refer to the same parts in all the figures.

A in the drawings represents the draw-head, which is provided with the longitudinal mouth B, at the sides of which recesses C C are formed. The said recesses have bearings in their upper and lower sides for the vertical pins or shafts D D, upon which wings E E are secured, as shown. The sides of these wings which face the front end of the mouth B are beveled or inclined, and their rear sides are square, as shown. The front ends of the wings E bear against the outer sides of the recesses C C, and they are thereby prevented from spreading or swinging outwardly. The rear ends of the wings may swing outwardly when forced in this direction by the coupling-link, as will be presently described. The lower ends of the pins or shafts D D extend through the bottom of the draw-head, and upon them are secured toothed segments F F, engaging each other, as shown. G is a spring secured to the under side of the draw-head in front of one of the said toothed segments, extending around the same, and pressing or bearing against its rear side. The shafts are thereby turned forwardly, and the wings E E held in the proper position for operation. One of

the shafts D extends upwardly through the draw-head, forming an operating-rod, H, by means of which the device may be manipulated in uncoupling.

I is the coupling-link, which consists simply of a cylindrical rod having pointed or arrow heads J at each end, as shown.

The operation of this invention will be readily understood from the foregoing description, taken in connection with the drawings hereto annexed. When the coupling-link enters the draw-head, it spreads the wings E E, between which it enters, and which are closed together in front of the head by the action of the spring G. To uncouple, the wings may be separated by simply turning the operating-rod, either directly or by any suitable mechanism. By means of the toothed segments the shafts D D are then turned in opposite directions, thus separating the wings and enabling the coupling-link to slide out.

My invention may be made available for other purposes than a car-coupling—for instance, as a lock or latch for gates, barn-doors, and the like. In Fig. 6 of the drawings I have thus shown it applied as a gate-latch, the part 75 designated as the draw-head being secured to the gate-post, and the gate being provided with an arrow-headed pin, or vice versa. This makes a strong, convenient, and inexpensive gate-latch.

Having thus described my invention, I claim and desire to secure by Letters Patent of the United States—

The combination of the draw-head A, having mouth B and recesses C C, wings E, shafts 85 D, having segmental gears F F, arranged under the draw-head, and the curved spring G, secured in front of one of said segments, extending around the same, and bearing against its rear side, as set forth.

In testimony that I claim the foregoing as my own I have hereto affixed my signature in presence of two witnesses.

GEORGE LIGHTHISER.
